UNITED STATES PATENT OFFICE.

CHARLES HENRY McNALLY, OF WAIPAHU, TERRITORY OF HAWAII.

SUGAR-CANE CONVEYER.

SPECIFICATION forming part of Letters Patent No. 702,813, dated June 17, 1902.

Application filed March 26, 1901. Serial No. 52,950. (No model.)

To all whom it may concern:

Be it known that I, CHARLES HENRY McNALLY, a citizen of the United States, and a resident of Waipahu, in the Island of Oahu 5 and Territory of Hawaii, have invented new and useful Improvements in Sugar-Cane Conveyers, of which the following is a full, clear, and exact description.

My invention relates to means for handling 10 sugar-cane, and has for its object to provide a self-propelled machine for conveying cane and loading it upon cars, thereby saving a large amount of manual labor and enabling 15 a comparatively small number of men to do the work which now requires six to seven times as many men.

The invention will be fully described hereinafter and the features of novelty pointed out in the appended claims.

Reference is to be had to the accompanying 20 drawings, forming a part of this specification, in which similar characters of reference indicate corresponding parts in all the figures.

Figure 1 is a plan of my improved self-propelled conveyer and elevator. Fig. 2 is a front 25 elevation thereof. Fig. 3 is a sectional elevation on the line 3 3 of Fig. 1. Fig. 4 is a sectional elevation on the line 4 4 of Fig. 3. Fig. 5 is a sectional detail on the line 5 5 of Fig. 4. Fig. 6 is a detail front view of the 30 driving mechanism and the conveyer, and Fig. 7 is a section on the line 7 7 of Fig. 2.

The improved cane conveyer and elevator is provided with a suitable frame 1, having 35 driving ground-wheels 2, journaled therein at each side. The frame carries a boiler 3, connected with independent steam-engines 4, each of which drives a shaft 5. Upon each shaft is mounted a pinion 6, engaging a gear-wheel 7 upon a shaft 8, from which motion is 40 transmitted by a pinion 9 and gear-wheel 10 to a shaft 11. With this shaft is mounted to turn, so as to be capable of sliding thereon, a clutch-section 12, movable lengthwise by 45 means of a shifting mechanism 13 and adapted to engage another clutch-section 14, held against lengthwise movement, but loose relatively to the shaft 11, except when the clutch-sections 12 14 engage each other. With the 50 clutch-section 14 is rigidly connected a bevel-wheel 15, engaging a similar wheel 16 on a shaft 17. This shaft carries a sprocket-wheel

18, connected by a chain 19 with another sprocket-wheel 20 upon a shaft 21. The two shafts 21 are provided with sprocket-wheels 55 22, receiving chains 23, consisting of inner links 24, alternating with outer links 24^a, and on the pivot-bolts 25 are loosely mounted between the inner links 24 collars 25^a. To the links are secured transverse plates 26, with 60 bolts 27 projecting between the links, and to said bolts are secured transverse slats 28, which together form a conveyer extending parallel with the axes of the driving-wheels 2. The frame 1 carries grooved guide-rollers 65 29, which engage the lower runs of the chains 23, and tension-rollers 30, Figs. 2 and 7, to take up slack.

On each of the shafts 11 is mounted to slide, yet held to turn therewith, a clutch-section 70 31, adapted to be moved by a shifting device 32 into engagement with another clutch-section 33, loosely mounted on the shaft, but held against longitudinal movement. With this clutch-section is rigid a pinion 34, engaging 75 a toothed rim 35 on the driving ground-wheel 2, Figs. 3 and 4.

At one end of the conveyer, formed by the slats 28, a trussed frame 36 is pivotally connected, as at 37, to the main frame 1. The 80 outer end of the frame 36 is adjustably supported by two rods 38, connected by a turn-buckle 39. The frame 36 carries an elevator 40, supported on sprockets 41, which receive the chains 42 of the elevator. The latter is 85 of the same construction as the conveyer, except that some of the slats 43 carry projections 44 for engaging the cane and keeping it from sliding down. The elevator is driven by means of sprocket-chains 45, passing over 90 wheels 46 on one of the shafts 21 and wheels 47 on the lower elevator-shaft 48, the wheels 46 being larger than the wheels 47, so as to drive the elevator at a higher rate of speed than the conveyer.

The frame 1 at the end opposite to the driving ground-wheels 2 carries forks 49, mounted to turn about vertical axes 50 and carrying 95 wheels 51. These forks when loose may be turned by suitable tools, or even manually. 100

In using the machine it is so placed as to travel lengthwise of the track on which stand the cars to be loaded with sugar-cane. The elevator 40 is arranged with its upper end

over the car. The sugar-cane is put on the conveyer at the end farthest away from the elevator and is carried along by the conveyer to the elevator, which raises it and dumps it 5 into the car. When a car is loaded, both wheels 2 are driven so as to bring the machine abreast of the next car, and then the operation is continued. The shifting devices 13 and 32 allow of starting the machine and 10 the conveyer and elevator or of keeping them stationary. The wheels 51 enable the machine to be steered. When it is desired to swing the machine around, only one of the wheels 2 will be driven, so as to cause the 15 machine to swing on the other wheel 2 as a pivot.

Having thus described my invention, I claim as new and desire to secure by Letters Patent—

20 1. A cane-loading machine comprising a frame provided with a driving ground-wheel on each side, two motors one at each side of the center of the frame, a clutch-controlled operating mechanism between each motor 25 and a driving-wheel, a conveyer mounted in the frame, and a clutch-controlled operating mechanism between each motor and the conveyer, as set forth.

2. A cane-loading machine, comprising a 30 frame provided with a driving ground-wheel on each side, two motors, one at each side of the center of the frame, a clutch-controlled mechanism between each motor and a driving-wheel, a conveyer extending transversely 35 of the frame, a clutch-controlled operating mechanism between each motor and the conveyer, and an elevator at one side of the frame and driven from the conveyer, as set forth.

40 3. A cane-loading machine comprising a supporting-frame, a pair of wheels at each side, one in front of the other of the frame, two motors, one at each side of the center of the frame, a clutch-controlled operating mechanism between each motor and one of the 45

wheels of a pair, a conveyer mounted in the frame and extending between the wheels of each pair, and a clutch-controlled operating mechanism between each motor and the conveyer, as set forth.

4. A cane-loading machine, comprising a 50 supporting-frame, a pair of wheels at each side of the frame one in front of the other, two motors, one at each side of the center of the frame, a clutch-controlled operating mechanism between each motor and one of the 55 wheels of a pair, a conveyer mounted in the frame and extending between the wheels of each pair, a clutch-controlled operating mechanism between each motor and the conveyer, an elevator adjustably connected with one 60 side of the supporting-frame, and means for operating the elevator from the conveyer, as set forth.

5. In a cane-loading machine, the combination with a wheel-supported frame, of a boiler on the frame, independent steam-engines on the frame one on each side of the boiler, and connected therewith, a conveyer mounted in the frame, and an operating mechanism between each motor and one of the supporting-wheels and the conveyer, as set forth.

6. In a cane-loading machine, the combination with a frame provided with a driving ground-wheel on each side, and a transversely-extending conveyer mounted in the frame, of two independent motors, shafts each having a clutch-controlled connection with one of the driving-wheels, gearing between each shaft and the conveyer, and clutch-controlled 75 gearing between each shaft and one of the motors, as set forth.

In testimony whereof I have signed my name to this specification in the presence of two subscribing witnesses.

CHARLES HENRY McNALLY.
